UNITED STATES PATENT OFFICE.

CLAUS J. WERNER CLASEN, OF DAVENPORT, IOWA, ASSIGNOR TO THE BETTENDORF COMPANY, OF BETTENDORF, IOWA, A CORPORATION OF IOWA.

UNDERFRAME.

1,178,493.

Specification of Letters Patent. Patented Apr. 11, 1916.

Application filed June 25, 1914. Serial No. 847,206.

To all whom it may concern:

Be it known that I, CLAUS J. WERNER CLASEN, a citizen of the United States of America, and resident of Davenport, Scott county, Iowa, have invented a certain new and useful Improvement in Underframes, of which the following is a specification.

My invention relates to improvements in metallic underframes for railway cars, and is directed more particularly to the construction thereof at the intersection of the body bolsters and center sills.

As is well understood by those skilled in the art, the longitudinal sills of a metallic underframe of high carrying capacity are given a "fish-belly" shape to meet a physical condition rather than with the thought of increasing the strength *per se* of the sill. The greater the load to be imposed on the sill, the greater the depths of the sill. In high capacity sills the depth would become so great, the ends could not clear the truck axles and at same time preserve the Master Car Builders' established limits of floor, center plate and coupler carrier heights; and hence the necessity of reducing the vertical height of the sill in the vicinity of the trucks, bringing about the fish-belly form.

To carry the load a sill is often 18 inches 30 to 30 inches deep at its center of length but must be reduced to 14 inches or 15 inches at the bolster to properly clear the truck and maintain Master Car Builders' regulation dimensions. It necessarily follows that 35 the vertical height of the body bolster at its intersection with the center sill is also limited to about 14 or 15 inches and that a union of the two be effected, of a nature to not exceed these dimensions. In underframes wherein the load is concentrated on the center sill, the bolsters may safely be made of a size to permit passing same through the center sill, but when the load is carried chiefly by the side sills the bolsters 40 must be sufficiently large and heavy to properly transmit the load to the trucks. In the latter case they are too large to be passed through the center sill.

It has ordinarily been the practice to 50 either cut the bolster or make it in two parts, permitting the center sill to pass between, or to cut the center sills and permit the bolsters to pass between.

My invention is directed to a construction 55 wherein both the center sill and the bolster

are continuous unbroken members, the bolster sufficiently large and strong to properly function in a side load carrying underframe and yet confining the dimensions of the members at their intersection in conformity with the Master Car Builders' regulations.

This I accomplish by the mechanism illustrated in the accompanying drawings, in which—

Figure I is a top plan view of one end of a steel underframe showing my improved method of intersecting a continuous center sill by a continuous bolster. Fig. II is a side elevation of the bolster, showing the center sill in section. Fig. III is a side elevation of a center sill near one end thereof, showing the bolster in section. Fig. IV is a perspective of the intersecting portions of the center sill and body bolster. Fig. V is a plan view similar to Fig. I showing my improved construction as applied to a double center sill. Figs. VI and VII are modifications of my improved construction, in which the bolster passes over the center 80 sill at the intersection instead of under.

Similar reference numerals refer to similar parts throughout the several views.

The flanged beam 1, to each end of which is riveted the metallic draft arms 2. 2. forms 85 the center sill of a steel underframe. While one end only of the sill is shown it is to be understood that both ends are finished alike. The ends of the flanged beam portion 1, are reduced vertically, leaving the central portion thereof the full height of the original beam, thus producing a "fish-belly" or truss shape sill extending continuously from end sill 3 to a similar end sill at the other end 90 of the underframe (not shown). The continuous one piece cast steel bolster 4 is of I section and extends from side sill to side sill 5—5. The upper chord of the bolster at its center of length and in the vicinity of its intersection with the center sill, is 95 depressed or notched out as at 6, while the lower chord or edge of the center sill is depressed or notched out as at 7. The bolster is brought into engagement with the recessed portion of the center sill from the under side, with the recessed portion of the bolster engaging the upper unbroken portion of the center sill. With the members thus interlocked their upper and lower surfaces are brought in the same planes. The 100 105 110

reinforcing plate 8 extending across the bolster depression is securely riveted to the bolster and center sill.

In underframes designed to carry all the load on the center sill, the bolsters merely functioning as cross bearers to support the floor nailings and stringers, can be relatively light and small, to an extent that they can be safely and readily passed through the center sill at their intersection therewith, but in underframes wherein the greater portion of the load is to be carried by the side sills and transmitted to the trucks through the medium of the bolsters, these bolsters must be made larger and heavier, to an extent that they cannot be passed through the center sill. When such heavier and larger bolsters were required, it has been customary, in the past, to resort to the built up type, that is, heavy, deep diaphragms extending from side sill to center sill and from center sill to side sill, with top and bottom splice plates. My invention therefore is directed to maintaining continuous unbroken members and yet employing a bolster sufficiently large and heavy to properly and safely function as a load transmitting member.

In Fig. V I show my improved construction as applied to a double center sill underframe wherein to the ends of rolled beam sills 9—9 are riveted the cast steel draft sills 10—10. The general construction would in all respects be similar to that shown in Fig. I as previously described, except as to the spacing of the draft sills, made necessary to meet the double center sill. There would be no change in the construction of the bolster except the widening of the recess to accommodate the spacing of the draft sills.

In Figs. VI and VII I show a modification of my improved structure, which consists in forming the recess in the bottom portion of the bolster 12 and upper portion of the center sill, 11, and applying the cover plate 13 to the top of the center sill although I would consider the former construction as the preferred form.

It will be observed that by thus notching out and interlocking the center sill structure with the bolster, I may utilize the center bearing 14 for the truck bolster to assist in tying the members together at their point of intersection. As shown in Fig. II, the preferred way of doing this is to fasten by rivets 15 the center bearing plate both to the underside of the center sill flanges as well as the underside of the bolster flanges, and form at the center of the bearing an upstanding cup 16 which bears upon the underside of the bolster, this cuplike upstanding part serving as usual to assist in centering the center bearing of the body bolster. It will be seen that in this way the upper

member of the body bolster bearing is utilized to assist in tying the center sill to the bolster. It will be understood, of course, that where, as in Fig. VI, the notch at the intersection of the members is formed in the bolster; then the upstanding cup part 16 will bear against the underside of the center sill structure.

What I claim as new is:

1. In an underframe for railway cars, the combination of end sills, side sills, center sills and body bolsters, said center sills extending from end sill to end sill, said bolster extending from side sill to side sill, and intersecting said center sill, said center sill provided with a recess in its under side at the point of intersection with the bolster, of practically half the depth of its vertical dimension, a center bearing plate spanning said recess and secured to said center sill and said bolster provided with a recess in its upper side at the intersecting point with the center sill of practically half the depth of its vertical dimension, and a tie plate spanning said recess and secured to said bolster. 50

2. In an underframe for railway cars, the combination of a continuous center sill extending from end to end of car, body bolsters extending continuously in one piece from side to side of the car interlocked by internotching with the said center sill and having their top and bottom surfaces, at the point of intersection in, practically, the same horizontal plane, and a tie plate spanning the notch in the member recessed in its upper surface, and a center bearing plate spanning the notch in the member recessed in its lower surface. 100

3. In an underframe for railway cars the combination of end sills and side sills, continuous center sills extending from end sill to end sill provided with recesses for the passage of body bolsters therethrough, continuous one piece body bolsters extending from side sill to side sill provided with recesses for the passage of the said center sill therethrough, and a cover plate secured to the upper surfaces of said members at the point of intersection, and a center bearing plate secured to the lower surfaces of said members at the point of intersection. 110

4. In an underframe for railway cars, the combination of a flanged beam, provided with metallic draft arms secured to the ends thereof and extending from end to end of the car, recesses in said draft arms for the passage of body bolsters therethrough, and center bearing plates spanning said recesses and secured to said draft arms and bolsters, one piece flanged beam body bolsters extending from side to side of the car provided with recesses for the passage of the said draft arms therethrough and cover plates spanning said recess and secured to said bolsters and draft arms. 125

5. In a car underframe, the combination of a center sill member, body bolster member intersecting the same, the two members being rigidly interlocked by inter-notching them at their point of intersection, a center bearing for the body bolster riveted to the undersides of both of said members outside the point of intersection and having an upstanding central portion bearing upon

the underside of the member which is 10 notched on its upper side.

Signed by me at Davenport, Iowa, this 23rd day of June, 1914.

CLAUS J. WERNER CLASEN.
